CLAIM

The ornamental design for an operational panel for an uninterrupted power supply, as shown and described.

DESCRIPTION

FIG. 1 is a perspective view of an operational panel for an uninterrupted power supply showing our design;

FIG. 2 is a front view thereof;

FIG. 3 is a top view thereof;

FIG. 4 is a bottom view thereof;

FIG. 5 is a side view thereof; and,

FIG. 6 is an opposing side view thereof.

The rear view is disclaimed and has been omitted.

The broken lines shown represent unclaimed subject matter and form no part of the claimed design.
